Attn:

UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A PLATE.

SPECIFICATION forming part of Design No. 24,201, dated April 16, 1895.

Application filed February 21, 1895. Serial No. 539,284. Term of patent 7 years.

To all whom it may concern:

Be it known that I, CHARLES C. WIENTGE, of the city of Providence, in the county of Providence and State of Rhode Island, have 5 invented and produced a new and original Design for a Plate, of which the following is a specification, reference being had to the accompanying drawing, forming part thereof.

The drawing represents a plan view of a 10 plate illustrating my new design.

The leading feature of the new design consists in the shell-like ornaments located at equal distances around the rim of the dish and connected with irregular scrolled outlines, together with surface ornamentation, 15 consisting of a combination of open-work scrolls extending inward from two of said ornaments oppositely located and form borders which are contracted in their extension until 20 they connect which the intermediate shell ornaments by a series of branched scrolls having their points of juncture in the intermediate scrolls.

In the drawing 5 indicates the rim of the 25 plate to which the design is applied.

6—6 are the side ornaments having irregular surfaces and turned-up edges giving a shell-like effect, the central portions having

the oval openings 7—7. From the sides of the ornaments 6—6 extend the foliated scrolls 30 8—8 which are extended by the branched scrolls 9, 10 and 11. The branches 11—11 are connected by the scrolls 13 and the shell-scroll 14 with the end ornaments, consisting of a series of oppositely arranged scrolls 35 15—15 and 16—16 finished at the outer portions by the scrolls 17—17 and the shell-like ornaments 18—18. The branches 9—9 are connected with the scrolls 17 by those marked 19—19 which in turn are connected by the 40 shell-like scrolls 20—20 with the ends of the branches 10—10 and with the scrolls 13, while between the scrolls 17—20 and 14 are located the scrolls 21—21. The spaces between the scrolls are cut away and the surface contours 45 being such as will accentuate the design.

What I claim is—

The design for a plate as herein shown and described.

In witness whereof I have hereunto set my 50 hand.

CHARLES C. WIENTGE.
